APPARATUS FOR CEMENTING SOLES TO
SHOE BOTTOMS

Maurice Barry, Chelsea, Mass.

Application January 5, 1938, Serial No. 183,473

12 Claims. (Cl. 12—36)

This invention relates to an apparatus for cementing soles to shoe bottoms, and particularly to an apparatus of the type comprising a plurality of connected traveling sole-pressing elements, each having an inflatable pad and means for holding a lasted shoe against the pad, together with means for inflating each pad after a shoe has been loaded into the corresponding shoe-pressing element.

10 In an apparatus of this type the inflating of the individual inflatable pads is accomplished through the medium of an inflating device in the form of an air-supply chuck that is adapted to be momentarily coupled to an air valve with which 15 each pad is provided, and one feature of my present invention relates to novel means for bringing the air-supply chuck and the air valve of each pad into registering alignment at the time that the pad is to be inflated.

20 In an apparatus of this type it is also customary to provide means for automatically deflating each pad as it approaches the loading position so that when the pad arrives at the loading position the shoe which is therein can be readily removed by the operator and replaced by another shoe having assembled therewith an outsole which 25 is to be cemented thereto.

Another feature of the invention relates to a 30 novel means for automatically deflating each pad as it approaches the loading position.

A still further feature of the invention relates to the construction of the portion of the shoe-pressing element which holds the shoe against the pad, and a further object of the invention is 35 to provide a novel construction which facilitates the removing of a finished shoe from the shoe-pressing element and loading another shoe thereinto to have the sole cemented thereto.

In order to give an understanding of the invention I have illustrated in the drawings a selected embodiment thereof which will now be described after which the novel features will be pointed out in the appended claims.

In the drawings:

45 Fig. 1 is a fragmentary sectional view of a portion of an apparatus for cementing soles to shoes embodying my invention;

Fig. 2 is a section on the line 2—2, Fig. 1;

Fig. 3 is a sectional view on the line 3—3, Fig. 1;

50 Fig. 4 is an enlarged vertical sectional view through the air valve of the pad and the air-supply chuck which illustrates the operation of delivering air to the pad;

Fig. 5 is an enlarged sectional view on the line 5—5, Fig. 2 illustrating the means for 55 bringing the air valve and air-supply chuck into

registering alignment and coupling them together in inflating relation;

Fig. 6 is a longitudinal sectional view through one of the sole-pressing elements;

Fig. 7 is a section on the line 7—7, Fig. 6;

Fig. 8 is a fragmentary detail view of the pad-deflating element;

Fig. 9 is a view illustrating the manner in which the valve of the pad and the air-supply chuck are automatically brought into registering alignment during the movement of the shoe-pressing element;

Fig. 10 is a fragmentary view showing the device for bringing the air-supply chuck and air valve into alignment.

As stated above, the device herein illustrated is of that type comprising a plurality of connected traveling sole-pressing elements, each having an inflatable pad and means for holding the shoe thereagainst, and in Fig. 1, 1 indicates a plurality of such sole-pressing units which are connected together in endless chain formation as indicated at 2. Each sole-pressing element is formed with a rigid box-like base portion 3 which is formed with a cavity or chamber 4 adapted to receive the inflatable pad 5. The pad herein shown is molded from rubber in the form of a seamless bag and the mouth of the bag is tightly closed or sealed by being clamped between two clamping bars 6 which are connected together by screws 7. If desired, the rubber bag 5 may be enclosed in an envelope 8 of leather or some other material which will withstand the wear occasioned by the sole-pressing operation.

Each shoe-pressing element 1 is provided with means for holding the lasted shoe against the pad and in the present embodiment of the invention such means is in the form of a yoke-shaped member 9 which extends from one end to the other of the base 3, and the arms 10 of which are pivotally connected to the ends of the base 3 as shown at 11. This bar 9 is formed with a projection or rest 12 to engage the toe portion of the lasted shoe 13 and is also provided with a second projection 14 adapted to engage the heel portion 15 of the last 15.

The operative position of the member 9 is the vertical position shown in Fig. 3 but when the pad is deflated the member 9 can be swung into an inclined position, thus removing it from the top of the lasted shoe thereby making it easy to remove the shoe from the shoe-pressing element.

The connected shoe-pressing elements 1 are shown as provided with guiding rolls 16 which 55

operate in channel-shaped tracks 17 that are carried by the frame 18 of the machine, and, as stated above, the various shoe-pressing elements are connected together in endless chain 5 formation. In the operation of the device these traveling sole-pressing elements have a continuous movement as distinguished from a stop-and-go movement.

Each inflatable pad is provided with an air 10 valve 19 which depends therefrom and through which air is supplied to the pad to inflate it and is exhausted from the pad to deflate it. The air valve may have any suitable or usual construction, and as shown in Fig. 4 it comprises a valve 15 casing 20 having a valve chamber 21 in which is received a valve 22 acted on by a spring 23 which tends normally to seat it against a valve seat 24. The valve has the stem 25 extending therefrom which normally projects beyond the valve casing. 20 The means for inflating each pad after a shoe has been loaded into the corresponding shoe-pressing element comprises an air-supply chuck 26 which is adapted to be coupled to the valve 19. The air-supply chuck herein shown has the same 25 construction as that illustrated in my co-pending application Serial No. 670,471, filed May 11, 1933, and it is provided with a valve chamber 27 which has communication with a supply pipe 28 leading to a source of compressed air supply, and it also 30 has a valve 29 in said chamber which is normally held closed against a valve seat 30 by the air pressure in the air chamber 27. This air-supply chuck is formed with a recess or cavity 31 directly above the valve seat 30 and of a size 35 to receive the end of the valve 19 of an inflatable pad. The chuck valve 29 has a winged extension 32 which is adapted to be engaged by the end of the valve 19 when the latter is inserted into the cavity 31 and which is also adapted to 40 engage the stem 25 of the valve 22. When, therefore, the chuck 26 is coupled to the pad valve element 19 both valves 29 and 22 will be open as shown in Fig. 4 so that air will be delivered from the supply pipe 28 into the inflatable pad 45 thereby to inflate the latter.

This chuck 26 is mounted on the outer end of a swinging arm 33 that is pivotally mounted at the inner end at 34 to a bracket 35 carried by the frame 18. The outer end of the arm is supported on a track 36 in the form of a bracket 50 which is secured to a portion of the frame 18, and for this purpose said arm 33 is provided near its outer end with a collar 37 carrying a roll 38 which rests on the track 36.

55 The chuck 26 normally occupies a position below the path of travel of the pad valves 19 and at one side of the vertical plane of said path. The coupling of the chuck to each valve 19 involves first a movement of the chuck transversely 60 of the path of travel of the valves to bring said chuck into the vertical plane in which the valves 19 travel, during which transverse movement of the chuck it is brought into registering alignment with the valve of the pad which is passing 65 through the loading zone, and then raising said chuck from its lowered position shown in dotted lines in Fig. 4 into its inflating position in which it is coupled to the valve 19 as shown in full lines Fig. 4.

70 It will be remembered that the sole-pressing elements are moving continuously and this coupling of the chuck to any valve 19 occurs during the movement of the sole-pressing element.

This operation of moving the chuck 26 trans- 75 versely to bring it into the plane of the path of

travel of the valves 19 and into registering alignment with the valve of the pad which is traveling through loading zone, and subsequently raising the chuck to couple it with said valve 19, is accomplished through the medium of a treadle 5 39 which is connected to and actuates an actuating lever 40 pivoted at 41 to a suitable stand or support 42.

The treadle 39 is shown as secured to the end 10 of a vertically moving treadle rod 43 which extends through and is guided by apertures in brackets 44, the upper end of said rod 43 being pivotally connected to the outer end of the lever 40 by a pin and slot connection 45. A spring 46 encircling the upper end of the rod 43 and confined between the upper bracket 44 and a collar 47 on said rod normally holds the rod and treadle in elevated position shown in Fig. 3 with the stop collar 48, which is fast to the rod 43, engaging the under side of the upper bracket 44 and thus 15 limiting the spring-impelled movement of said rod.

To provide for the lateral movement of the chuck 26 from its inoperative position shown in Fig. 3 to a position in the vertical plane of the 25 path of travel of the valves 19, I propose to make the arm 33 so that it can be extended in the direction of its length. Accordingly said arm embodies in its construction two members 49 and 50 which have a telescopic relation, the member 30 49 being a tubular member within which the member 50 telescopes. The member 50 carries at its outer end a head 51 having a seat 52 on which the chuck member 26 normally rests, said member having a depending stem 53 which extends through and is adapted to slide in an aperture 54 with which the head 51 is provided. The extensible section 50 of the arm 33 is so connected to the actuating lever 40 that when said lever is rocked counterclockwise by the depression of the 40 treadle 39 said arm section 50 will be moved outwardly into its extended position thereby carrying the chuck member 26 into the vertical plane of movement of the traveling valves 19. For this purpose I have provided a toggle device comprising two toggle members 55, 56 pivotally connected at 57, the member 55 being pivoted at 58 to a collar 59 which is clamped to the arm section 49, and the toggle member 56 being pivotally connected at its outer end to the upper end of a pin 50 60 which extends through the arm section 50 and operates in a slot 61 with which the tubular arm section 49 is provided. The toggle member 50 is connected by a link 62 to the actuating lever 40. 45

When the extensible arm 33 is in its normal 55 contracted condition as shown in Fig. 3 the toggle device will be partially folded, this being the position of the parts when the actuating lever 40 is in its normal position. The depression of the treadle 39 will move the actuating lever 40 counter-clockwise and this movement of the lever operates through the link 62 to straighten the toggle, thereby moving the arm member 50 outwardly into the position shown in Fig. 5 and thereby 60 bringing the chuck member 26 into the vertical 65 plane of the path of travel of the valve 19.

In order to bring the chuck and the valve 19 into registering alignment at the time that the chuck 26 is moved outwardly into said vertical 70 plane, I have provided a chuck-aligning device 63 which is carried by an upright arm 64 rising from the arm section 50. This chuck-aligning device 63 is in the form of a plate having the two converging valve-engaging edges 65 which terminate 75

at their inner ends in a seat portion 66 of a size to fit the valve 19.

The inflating mechanism above described is situated in the loading zone, that is, the zone in which each sole-pressing element is traveling at the time that the operator loads a shoe into it. Inasmuch as the shoe-pressing elements are moving continuously through the loading zone the operator has to use his judgment as to the proper time to depress the treadle. The chuck-aligning member 63 has sufficient dimension in the direction of the travel of the valves 19 so that a considerable time element will be required for each valve to pass the chuck-aligning member 63. When each sole-pressing element arrives within the loading zone the valve 19 thereof will be located at some point opposite the edge of the chuck-aligning member 63, and when the operator depresses the treadle 39 and moves the chuck 26 and chuck-aligning member 63 transversely the valve 19 will be engaged either by one of the inclined valve-engaging edges 65 or by the seat portion 66. If the valve is engaged by one of the inclined valve-engaging edges 65 as shown in Fig. 10 the pressure of the chuck-aligning member against the valve will cause the arm to swing about its pivot and the valve to slide down the inclined edge 65 into the seat 66. This seat 66 is positioned directly over the cavity 31 in the chuck, and when the valve is seated in the seat 66 the chuck and the valve will be in registering alignment, and said chuck can be coupled to the valve by being moved upwardly from the dotted to the full line position in Fig. 4. This coupling movement of the chuck which brings the chuck into inflating position is given to it by the lever 40. The outer end 67 of the lever is formed with an extended flat surface 68 and the stem 53 of the chuck has at its lower end a head 69 carrying a roll 70 which is adapted to be engaged by the surface 68 of the lever during the final portion of its operative movement, and thereby the chuck is raised into its inflating relation with the valve.

It will thus be seen that during the initial operative movement of the lever 40 the arm 33 is extended to bring the chuck into the vertical plane of movement of the valve 19 and simultaneously the chuck and the chuck-aligning member 63 cooperate to bring the valve and chuck into registering alignment, and during the final movement of the lever 40 the chuck is raised into its inflating position with relation to the valve shown in full lines Fig. 4.

To provide for the continued swinging movement of the lever 40 after the toggle has been straightened and the valve 19 has been seated in the seat portion 66 of the chuck-aligning member, I propose to make the toggle member 56 capable of having a telescoping action. This member is formed with an outer tubular section 71 and an inner section 72 which telescopes within the tubular member 71, the inner member having a pin 73 operating in a slot 74 with which the tubular member is provided and which allows the telescoping action but prevents separation of the two sections 71 and 72. A spring 75 is located within the tubular member 73 and bears against the inner end of the section 72, said spring normally holding the two members in their extended relation shown in Fig. 3.

The spring 75 is sufficiently strong so that it will resist any telescoping action of the two members 71, 72 until the arm 33 has been extended and the valve 19 has been brought into the seat 66 of the chuck-aligning member.

When this occurs further extending movement of the arm is prevented and as the lever 40 continues its operative movement the spring 75 will yield to allow the member 72 to telescope within the tubular member 73 as shown in Fig. 5. In operating the device the operator, who stands within the loading zone, will load each shoe-pressing element 1 with an assembled shoe and outer sole as said press arrives at said loading zone, it being understood that the pad is deflated at this time. As soon as the shoe-pressing element has thus been loaded the operator will depress the treadle 39, thereby first bringing the chuck and the valve of the loaded shoe-pressing element into registering alignment, and then raising the chuck member into their coupling arrangement with said valve. This results in inflating the pad, an operation which takes place during the traveling movement of the shoe-pressing element. The pivotal mounting for the arm 33 and the telescopic structure of said arm not only provides for thus bringing the chuck into inflating relation with the valve but also permits the chuck to partake of the straight-line movement of the valve during the inflating operation. When the pad is fully inflated the operator releases the treadle and the spring 46 raises the latter and moves the lever 40 clockwise into the position shown in Fig. 3. During the first part of this clockwise movement the chuck 26 drops from the full to the dotted line position, Fig. 4, and during continued clockwise movement of said lever the toggle device 55, 56 is folded and the arm 33 is contracted, thereby moving the chuck 26 into its normal position at one side of the plane of travel of the valve. The arm 33 is shown as having two centering springs 76 connected thereto by which it is normally held in central position, said springs operating to return the arm to this position after it has released the valve.

I have also provided herein means for automatically deflating each pad just before it arrives at the loading zone, thus releasing the shoe therein so that it can be removed by the operator. The deflating device herein shown comprises an arm 77 pivotally mounted at 78 and carrying at its outer end a block 79 which is pivoted to the arm at 80 to permit vertical swinging movement of said block. This block 79 has a roller 81 which rides on a track 82, the latter being provided with a raised cam portion 83. Secured to the outer end of the arm 77 is a bracket 84 having at its upper end a laterally extending valve-engaging flange 85, the latter being situated in position to be engaged by each valve 19 during its traveling movement. The arm 77 is acted on by a spring 86 which normally holds it in its retracted position shown in Fig. 8 with the block resting against a stop 87.

As each sole-pressing element 1 approaches the loading zone the valve 19 thereof will engage the flange 85 so that during further forward traveling movement of the sole-pressing element the arm 77 will be swung to the right from the dotted line position to the full line position in Fig. 9.

At the time that the valve 19 engages the flange 85 the end of the valve stem 25 will be situated directly over the block 79, and as said arm is swung toward the right, Fig. 8 by the forward movement of the valve 19 the block 79 will be moved over the hump 83. This will swing the block upwardly into the position shown in Fig. 1, thereby bringing it against the projecting end of the valve stem 25 and unseating the valve 22, 75

thereby allowing the air within the pad to escape. As the valve 19 continues its forward movement the block 79 will pass off from the hump 83, and as said arm 77 moves slightly beyond the full line position in Fig. 9 the flange 85 will become disengaged from the valve, at which time the spring 86 will return the arm 85 and block 79 to its normal position with said block against said stop 87.

10 I have referred above to the construction of the sole-pressing element including the pivotally mounted yoke portion 9.

The machine herein shown is provided with means for automatically swinging the yoke 9 of each sole-pressing element from its upright position to its inoperative position just after the pad of said element has been deflated, thus carrying said yoke away from the shoe so that the operation of removing the shoe from the pad is facilitated. The machine is provided with a bar 88 extending transversely of the direction of movement of the sole-pressing elements and situated to be engaged by the yoke 9 of each sole-pressing element just after the pad thereof has been deflated. The engagement of this bar 88 with the yoke swings the yoke backwardly into its inoperative position as shown in Fig. 1.

The machine herein shown is also provided with means for returning the yoke 9 to its operative position just before the shoe-pressing element reaches the loading zone so that when the operator loads a shoe into said element the yoke 9 is in its operative position. For this purpose one of the arms 10 of each yoke extends below its pivotal point 11 and is provided with a cam portion 89 adapted to engage a plate 90 secured to one of the channel tracks 16. The engagement of the cam end 89 of the arm 90 with said plate causes the yoke 9 to be swung back into its operative position.

40 I claim:

1. A machine for cementing soles to shoe bottoms comprising a plurality of connected sole presses having a continuous traveling movement past a loading position, each sole press comprising an inflatable pad and means for holding a shoe there-against, and having a depending air inlet valve, an air supply chuck adapted to be coupled to said valve, a swinging extensible arm on which said chuck is mounted, said chuck normally occupying a position at one side of the vertical plane of travel of said valve, means operable to extend said arm to bring the chuck into said plane and into registering alignment with the valve during the forward movement of the sole press, and thereafter to move the chuck into inflating relation with said valve.

2. An apparatus for cementing soles to shoe bottoms, said apparatus having a plurality of connected sole presses having a continuous traveling movement past a loading position, each sole press comprising an inflatable pad and means for holding a shoe there-against, and also having a depending air inlet valve, an air supply chuck adapted to be coupled to said valve, a swinging extensible arm on which said chuck is mounted, said chuck normally occupying a position at one side of the vertical plane of travel of said valve, manually actuated means to extend said arm thereby to bring the chuck into said plane, a chuck aligning member carried by said arm and adapted to engage the valve as the arm is extended and bring the chuck and valve into registering alignment and means to move the chuck into inflating relation with the valve.

3. An apparatus for cementing soles to shoe bottoms, said apparatus having a plurality of connected sole presses having a continuous traveling movement past a loading position, each sole press comprising an inflatable pad and means for holding a shoe there-against, and also having a depending air inlet valve, an air supply chuck adapted to be coupled to said valve, a swinging extensible arm on which said chuck is mounted, said chuck normally occupying a position at one side of the vertical plane of travel of said valve, manually actuated means to extend said arm thereby to bring the chuck into said plane, a chuck-aligning member carried by said arm and having valve-engaging faces which converge to a seat portion and which are adapted to engage the valve as the arm is extended thereby to bring the chuck and valve into registering alignment, and means to move the chuck into inflating relation with the valve.

4. A device of the class described comprising a plurality of connected traveling sole presses, each having an inflatable pad and means for holding a shoe there-against, and also having an air inlet valve, an air supply chuck, a swinging extensible arm on which said chuck is mounted, said chuck normally occupying a position at one side of the path of movement of the air supply valve, an actuating lever, means to give it an operative movement, means actuated by initial movement of the lever to extend the swinging arm and bring the chuck into registering alignment with the valve, and means actuated by the lever during its final movement to bring the chuck and valve into coupling relation.

5. A device of the class described comprising a plurality of connected traveling sole presses, each including an inflatable pad, means for holding a shoe there-against and an air inlet valve, an air supply chuck, a swinging extensible arm on which said chuck is mounted, said chuck normally occupying a position at one side of the path of movement of the air inlet valve, a manually operated actuating lever, means operated by said lever during its initial movement to extend the arm and bring the chuck into the path of movement of the valve, a chuck-aligning member carried by said arm and adapted to engage the valve as the arm is extended thereby to bring the chuck and valve into registering alignment, and means operated by the lever during its final movement to bring the aligned chuck and valve into coupled relation.

6. A machine for cementing soles to shoe bottoms comprising a plurality of connected sole presses having a continuous traveling movement which carries each press through a loading zone, each sole press having an inflatable pad, means for holding a shoe thereagainst and a depending air inlet valve, an air-supply chuck normally situated at one side of the vertical plane of travel of the air valves of said presses, means to move said chuck into said vertical plane of travel, means moving with the chuck and cooperating with the air inlet valve of any press traveling through the loading zone to bring the chuck and valve into registering alignment, and means to move the chuck into inflating relation with said valve.

7. A machine for cementing soles to shoe bottoms comprising a plurality of connected sole presses having a continuous traveling movement which carries each press through a loading zone, each sole press having an inflatable pad, means for holding a shoe thereagainst and an air inlet

- valve, means for inflating each pad as it passes through the loading zone, a pad-deflating member situated in advance of the loading zone and capable of moving in the direction of travel of the inlet valves, means for coupling each valve to said pad deflator as the corresponding pad approaches the loading zone, and means for actuating the deflator during its traveling movement with the valve to deflate the pad.
- 10 8. A machine for cementing soles to shoe bottoms comprising a plurality of connected sole presses having a continuous traveling movement which carries each press through a loading zone, each press having an inflatable pad, means for holding a shoe thereagainst and an air inlet valve, means to inflate each pad as it travels through the loading zone, pad-deflating means to deflate each pad before it reaches the loading zone, said pad-deflating means including a deflating element capable of having a limited movement in the direction of travel of the valves, means to couple said pad-deflating element to each valve as the corresponding pad approaches the loading zone, and a stationary cam member adapted to engage the pad-deflating member as it is being moved by the valve thereby to cause said deflating member to deflate the pad.
9. A machine for cementing soles to shoe bottoms comprising a plurality of connected sole presses having a traveling movement which carries each press through a loading zone, each press having an inflatable pad and a depending air inlet valve provided with a projecting stem, means to inflate each pad as it passes through the loading zone, pad-deflating means comprising a deflating block, a track over which the block moves in the direction of the travel of the valves, and means for coupling said block to each valve as the corresponding pad approaches the loading zone, said track having a cam portion over which the block travels when it is coupled to a valve, whereby the block is raised into engagement with the valve stem thereby to deflate the pad.
- 40 10. A machine for cementing soles to shoe bot-

toms comprising a traveling sole press which moves through a loading zone, said sole press having an inflatable pad and a shoe hold-down member which holds the shoe against said pad and which is pivotally mounted to turn about an axis extending lengthwise of the shoe, and means adapted to engage each hold-down member as the corresponding pad approaches the loading zone thereby to swing said member about its axis into inoperative position.

11. A machine for cementing soles to shoe bottoms comprising a traveling sole press which moves through a loading zone, said sole press having an inflatable pad and a pivotally mounted shoe hold-down member which holds the shoe against said pad, means adapted to engage each hold-down member as the corresponding pad approaches the loading zone thereby to swing said member into inoperative position, and means cooperating with said hold-down member and rendered operative by the traveling movement of the sole press at a point farther on its journey and just before it reaches the loading zone to restore the hold-down member to operative position, whereby said hold-down member is in operative position when the shoe is loaded into the shoe press.

12. A machine for cementing soles to shoe bottoms comprising a plurality of connected sole presses having a continuous traveling movement past a loading position, each sole press comprising an inflatable pad and means for holding a shoe thereagainst and each sole press having a depending air inlet valve, an air supply chuck adapted to be coupled to said valve, means supporting said chuck normally in a position at one side of the vertical plane of travel of said valve, and means operable to move the chuck laterally into said plane and into registering alignment with the valve during the forward movement of the sole press and thereafter to move the chuck upwardly and into inflating relation with said valve.

MAURICE BARRY.
